[57] CLAIM

The ornamental design for a cosmetic kit, substantially as shown and described.

DESCRIPTION

FIG. 1 is a perspective view of a cosmetic kit in its closed position, showing my new design;

FIG. 2 is a similar view thereof with the cover partially open;

FIG. 3 is a top plan view thereof with the cover wide open and the top tier slid apart to disclose a lower tier;

FIG. 4 is a top plan view thereof in closed position;

FIG. 5 is a bottom view thereof;

FIG. 6 is a front view thereof;

FIG. 7 is a rear view thereof;

FIG. 8 is a left side elevational view thereof; and

FIG. 9 is a right side elevational view thereof.
